UNITED STATES PATENT OFFICE

163,794

WARNING SIGN

John V. Duda, Chicago, Ill.

Application April 29, 1950, Serial No. 9,598

Term of patent 3½ years

(Cl. D72—1)

To all whom it may concern:

Be it known that I, John V. Duda, a citizen of the United States, residing at Chicago, Cook County, Illinois, have invented a new, original, and ornamental Design for a Warning Sign, of which the following is a specification, reference being had to the accompanying drawing, forming a part thereof.

In the drawing:

Fig. 1 is a front elevational view of a warning sign showing my new design; and

Fig. 2 is a side elevational view thereof.

The dominant features of my design reside in the portions shown in solid lines in the drawing. The back of the design is plain.

I claim:

The ornamental design for a warning sign, as shown and described.

JOHN V. DUDA.
